BRASSIÈRE

Lenore B. Cooley, New York, N. Y.

Application October 25, 1947, Serial No. 782,154

3 Claims. (Cl. 2—42)

1

The present invention relates to brassières and, more particularly, to a readily adjustable brassière, which is simple to manufacture and which provides full support for and separation of the breasts.

Heretofore, it has been necessary to provide a number of bust cup sizes in a line of brassières to obtain a proper fit in each individual case. Not only a large range of bust cup sizes is necessary, but the garment itself must be manufactured in several sizes. Heretofore, the number of sizes of the garment has in general embraced a large series of sizes, namely, from size 32 to size 54, which, however, did not provide the proper general fit of the garment in all cases. For each size of the series of sizes, a large number of bust cup sizes is needed. The bust cup sizes are generally three in number. The principal disadvantages of brassières of the prior art are, therefore, increased costs and the necessity for providing large dealer stocks.

In accordance with the present invention, it is possible to eliminate the necessity for providing bust cups generally considered as such and, therefore, bust cups of different sizes. Also in accordance with the invention, the garment is simple and readily constructed since it is made up of two principal pieces, plus shoulder straps and closures for holding the garment on the upper body of the wearer. Moreover, in accordance with the invention, a normal and comfortable position of the breasts is provided. The means for maintaining the garment generally in the proper position vertically on the body, for example with respect to the shoulders, provides separation and lift-up of the breasts to a normal position. More specifically, where the garment of this invention is provided with two shoulder straps, adjustment of the shoulder strap on the left-hand side lifts up and holds the right breast in position, and adjustment of the right shoulder strap lifts up and holds the left breast in position. The adjustable means for the straps, therefore, have a combined function. They not only maintain the entire garment vertically in position on the body but provide for youthful separation and up-lift.

The principal object of the present invention, therefore, is to provide a brassière which will fit and support breasts of all sizes.

Another object is to provide a brassière constructed primarily of two pieces or breast supporting parts.

A further object of the invention is to provide a brassière having novel breast supporting means adapted to support a breast of any size in normal and comfortable position, thereby to give the figure line of the wearer a pleasing appearance.

A still further object of the invention is to provide novel adjusting means for both the size and "lift" of a brassière.

2

Other objects and advantages of the present invention will, of course, become apparent and immediately suggest themselves to those skilled in the art to which the invention is directed from the reading of the following specification in connection with the accompanying drawing in which:

Fig. 1 is a view of front elevation of a brassière constructed in accordance with the invention as it appears when worn.

Fig. 2 is a view of the brassière of Fig. 1 shown separately.

Figs. 3 and 4 are each a plan view of one of the two patterns for the two principal parts of a brassière of the present invention.

Fig. 5 is a view similar to Fig. 1, but showing a slight modification.

Fig. 6 is a fragmentary view similar to Fig. 3, or Fig. 4, showing a modified pattern for one of the parts of the brassière of Fig. 5.

Referring to the drawings, and for the present to Figs. 1 to 4, thereof, reference character 10

will be employed to represent the brassière in its entirety. The main part of the garment, that is the bust supporting portion, comprises two pieces of cloth 12 and 14 which are cut in accordance with the pattern 16 of Fig. 3, and the pattern 17 of Fig. 4, respectively. The solid and dotted lead lines of the reference characters 12

and 14 as they are used in Fig. 2 indicate portions of one which overlap and hide the other. Inasmuch as the pattern for Fig. 3 is substantially identical with that of Fig. 4, a detailed description will be given of the pattern 16 of Fig. 3. The piece of cloth 12 cut in accordance with this pattern is or may be stitched along the lines 18 and 19 to form a tuck or dart at 21 (Fig. 2). The piece of cloth 14 also has a tuck or dart 21. The general location and size of this tuck or dart is not critical, and in some instances it may be omitted.

Stitch lines for pleating are indicated at 22 and 23 so as to provide a suitable finish to the garment when tucks or pleats 26, as shown in Fig. 1, are taken on these lines. The tab or projection 27 is preferably provided (and is repeated in the part 12) to which one end of a shoulder strap 28 is secured in any suitable manner, for example, by stitching. The end 29 of the cloth (piece 12) cut according to the pattern

16, and also the end 30 of the cloth piece 14 cut according to the pattern 17, are available for receiving the end of one part of a suitable fastening or closure means. As shown in Figs. 1 and 2 of the drawings this closure means comprises a hook 31 and elastic straps 33 provided with a tape 36. The tape 36, or the like, is provided with suitable means such as spaced holes 38 to cooperate with the hook 31 when the garment 10

is worn. The spacing of the holes 38 provides for adjustment to suit the girth of a wearer. It will be understood that any closure means known

to the art may be used, the hook 31 and the tape 36 being shown by way of example.

The parts or pieces 12 and 14 are stitched together only along lines substantially at the darts 21 and cross substantially midway between these stitched lines, as indicated generally by reference character 43 of Figs. 1 and 2 of the drawings.

Considering the piece 12, it is seen to overlie the left breast of a wearer and to lie under the right breast. The shoulder strap 28 is secured to this piece at its tab 27 and to the end 29 of this piece. It is shown as passing over the left shoulder of the wearer. Suitable adjusting means for adjusting the length of the strap 28 is provided in accordance with the invention. By way of example, an adjusting buckle 48 is shown. It may be of any type known to the prior art which may be slid along the strap 28 in the usual and known manner to adjust its length or a loop of its length.

A strap 51, similar to the strap 28, is connected to the tab 27 on the piece 14, and this strap is also provided with length adjusting means such as a buckle 52 or its equivalent. Adjustment of the length of the strap 51, which is shown as being on the right side of the garment, as it is worn, lifts up and holds the left breast of the wearer. These straps 28 and 51 may be adjusted independently by the wearer after the garment 10 is in position so that perfect support and separation result irrespective of the size of the parts to be lifted, separated and held in position.

It will be noted that the pieces or parts 12 and 14 are not twisted in assembly of the garment. These pieces, as shown in Fig. 2, are crossed at 43, as described above. The piece 12 is under the piece 14 at the region 43 and the piece 14 is over the piece 12 at the region of 53. When the garment is in use, as indicated in Fig. 1, the cross-over portion 43 lies between the breasts and the points where the pieces 12 and 14 are side by side occur substantially at the middle of each breast. The fabric covers the breast entirely, or the nipple or the nipple region may be exposed and the breasts molded into their normal contour.

While stitching has been referred to in the foregoing it will be understood that any other means of joining the parts may be practiced, and darts, tucks and the like may be dispensed with if desired. With adjustability in girth provided by the holes 38, or their equivalent, a wide range of girth adjustment is possible. Substantially complete adjustment of support is obtainable as stated previously by adjusting the upward tension of the straps 28 and 51 so that the supporting and confining portions of the garment will fit the wearer. It is to be further noted that the garment departs from the usual practice in that no bust cups as such or parts corresponding to the usual bust cups need be provided, or are provided in accordance with the invention.

Fig. 5 of the drawings shows a slightly modified arrangement. Inasmuch as many of the parts are similar in Figs. 1 and 5, similar reference characters will be used with the suffix "a" added. In Fig. 5 there are two main parts or pieces 12a and 14a. One of these, for example, part 12a is provided with a slit 62 through which the other part 14a is passed during assembly of the garment. The cross-over region 43a then comprises an "interleaving" of the parts. The parts are freely movable with respect to each other at the region 43.

The patterns which are used as guides in cut- 75

ting the cloth of the main pieces are similar to the patterns 16 and 17 shown in Fig. 1 of the drawings. However, one of these, for example the pattern 66, corresponding to the pattern 16, for example, is marked with a line 68 as shown by Fig. 6 of the drawings as a guide for slitting the cloth piece 12. In view of the foregoing complete description of the modification of Figs. 1 and 2 of the drawings, it is believed that further description of the modified form of Fig. 5 and its use need not be given at this time.

This brassière is particularly adaptable to broad breasts because it permits the breast to remain in its normal contour due to the flexibility of the free cross-over of the fabric.

Pendulous or drooping breasts are molded to their normal contour, uplifted and held in place. The methods by which the fabric crosses over in the center front and the straps are adjusted, keep 20 the breasts separated and held in the correct position.

Young women, participating in athletics, will find the garment nonconstricting, allowing maximum flexibility and at the same time controlling 25 and supporting the breast tissue.

In addition, the brassière fits perfectly over normal round and pointed breasts molding them into their normal contours and supporting them in correct position with no constriction.

The invention claimed is:

1. A brassière comprising two pieces of material, each piece being at least of a length substantially to span the two breasts of the breast region of a wearer, said pieces being joined adjacent each end in substantially superimposed overlapping relationship and being crossed at the center of the brassière and freely movable at the center with respect to each other, the end of the first piece overlying the end of the second piece at one end of the joined pieces whereby said second piece provides supporting means under one breast of the wearer, and at the other end of the joined pieces with the second piece underlying the first piece whereby said first piece provides support 45 under the other breast of the wearer, and said brassière having body encircling means.

2. The brassière of claim 1 wherein said brassière is provided with a pair of shoulder straps, one shoulder strap being connected to the first 50 piece of material at a point remote from the end where it provides support under a breast of a wearer, the other shoulder strap being connected to said second piece of material at a point remote from the end where it provides support under a 55 breast of the wearer, said shoulder straps being connected to said body encircling means.

3. The brassière having the structure of claim 1 wherein one of said pieces of material has a slit therein, the other of said pieces passing 60 through said slit at said crossing.
